[57] CLAIM

The ornamental design for a cookware radially grooved exterior bottom surface, as shown and described.

DESCRIPTION

FIG. 1 is a perspective view of a cookware radially grooved exterior bottom surface showing my new design;

FIG. 2 is a top plan view thereof;

FIG. 3 is a left side elevational view thereof;

FIG. 4 is a rear elevational view thereof;

FIG. 5 is a right side elevational view thereof;

FIG. 6 is a bottom plan view thereof;

FIG. 7 is a front elevational view thereof; and,

FIG. 8 is a vertical cross-sectional view along line 8—8 of FIG. 7 transversely through a single radial groove shown in enlarged scale.

The cookware shown in phantom lines depicts the environment of my new design and forms no part of the design of my invention.
